UNITED STATES PATENT OFFICE.

JOSEPH RIEGELMAN, OF NEW YORK, N. Y.

DESIGN FOR FABRIC FOR DRESS-BELTS.

SPECIFICATION forming part of Design No. 34,518, dated May 14, 1901.

Application filed April 9, 1901. Serial No. 55,113. Term of patent 8½ years.

To all whom it may concern:

Be it known that I, JOSEPH RIEGELMAN, a citizen of the United States, and a resident of the city of New York, borough of Manhattan, in the county and State of New York, have invented and produced a new and original Design for Fabrics for Dress-Belts, of which the following is a specification, reference being had to the accompanying drawing, forming a part thereof, in which is represented a plan view of a portion of the fabric embodying the features of my design.

The leading features of the design consist in the transversely-coiled ornamental figures A at the central portion of the strip and the marginal longitudinally-arranged V-shaped ornamental figures B, both of which figures A and B appear embossed.

The minor features of the design consist in the rosette figures C, appearing between the coil and V-shaped figures, together with the plain margin D.

Having thus described my invention, I claim as new and desire to secure by Letters Patent—

The design for a fabric for dress-belts, herein shown and described.

In testimony whereof I have signed my name to this specification in the presence of two subscribing witnesses.

JOSEPH RIEGELMAN.
